CLAIM

The ornamental design for a combined four stone round
gemstone arrangement with setting, as shown and described.

DESCRIPTION

FIG. 1 is a top perspective view of a combined four stone
round gemstone arrangement with setting in a setting
embodiment my new design showing the stem in broken
lines; and,

FIG. 2 is a top perspective view of a four stone round
gemstone arrangement with setting in a second setting
embodiment my new design, showing the stem in broken
lines.

The broken line showing of the stem is for illustrative
purposes only and forms no part of the claimed design.
